UNITED STATES PATENT OFFICE

LENA LILLIAN LUCE, OF BROCTON, NEW YORK

BUCKLE SHIELD FOR GARTERS

Application filed March 27, 1931. Serial No. 525,791.

This invention relates to a shield for the buckles of garters, the general object of the invention being to provide means for covering the buckles and stocking engaging members of a garter so as to prevent these parts from injuring other garments, such as by causing runs in silk bloomers or the like.

This invention also consists in certain other features of construction and in the combination and arrangement of the parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a view of a portion of the garment supporter showing the invention in use.

Fig. 2 is an edge view of Fig. 1.

Fig. 3 is a view showing the buckle shield in detached position.

Fig. 4 is a view looking toward the rear of a part of the garter showing the buckle shield in partly folded position.

Fig. 5 is a view of the shield for covering the stocking engaging member of a garter.

Fig. 6 is a part of said stocking engaging member showing portions of snap fasteners thereon.

In these views, the web of the garter is shown at 1, the buckle at 2, and the stocking engaging member at 3. In carrying out my invention, I provide a shield A for covering the buckle 2 and a shield B for covering the stocking engaging member. The shield A consists of an elongated strip of any suitable material, having a tongue 4 at one end thereof, the outer end of which is sewn or otherwise attached to the rear face of the webbing as shown at 5. This shield A is adapted to be passed around the webbing and over the buckle 2 and then its free end is connected by the fastening parts 6 carried by said free end to the fastening parts 7 at the end to which the tongue is connected.

Thus this shield forms a band around the webbing and covers the buckle 2 so as to prevent this buckle from injuring articles of

clothing such as by causing runs in bloomers or the like.

The shield B consists of an elongated strip of any suitable material and tapers from its upper end to its lower end, with its upper end suitably sewn to the part 8 of the garter, and in such a manner that the shield covers the stocking engaging member 3, and its loop 3' so as to prevent these portions from coming into contact with the garment to injure the same.

The lower end of the stocking engaging member is formed with the fastening parts 9 for engaging the fastening parts 10 on the lower end of the shield B so as to detachably connect the lower end of the shield B with the lower end of the member 3.

From the foregoing, it will be seen that I have provided simple forms of shields for the buckles and stocking engaging parts of a garter, which can be easily and quickly adjusted to a position where the parts are accessible, and then easily and quickly placed in a position to cover such parts to prevent such parts from contacting the bloomers or other wearing apparel.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described my invention, what I claim as new is:—

In combination with a buckle of a garter, a shield having one end connected with a part of the garter, said shield passing around the garter and the buckle and means for detachably connecting the free end of the shield to the other end thereof.

In testimony whereof I affix my signature.

LENA LILLIAN LUCE.
